UNITED STATES PATENT OFFICE.

EDGAR B. HANDS, OF SHREVEPORT, LOUISIANA.

THERMOSTATIC FUEL-VALVE.

1,257,602.

Specification of Letters Patent. Patented Feb. 26, 1918.

Application filed September 22, 1916. Serial No. 121,648.

To all whom it may concern:

Be it known that I, EDGAR B. HANDS, a citizen of the United States, residing at Shreveport, in the parish of Caddo and State of Louisiana, have invented a new and useful Thermostatic Fuel-Valve, of which the following is a specification.

The object of the invention is to provide a simple and efficient construction of valve 10 adapted to be used in connection with the gasolene feed of a carbureter under such conditions as will insure an economical feed of the fuel when the running conditions of the engine are favorable for a reduction in richness of the mixture, whereas the reverse 15 action is effected when an increased richness of the mixture is necessary, said operation being effected automatically and without requiring the attention or manipulation of the 20 operator.

Further objects of the invention will appear as the description proceeds, it being understood that changes in the precise embodiment of the invention herein disclosed, 25 can be made within the scope of what is claimed, without departing from the spirit of the invention.

In the accompanying drawings:—

Figure 1 is a view of the valve construction embodying the invention arranged in operative position in a carbureter a portion of which is illustrated.

Fig. 2 is a detail sectional view of the valve on the plane indicated by the line 2—2 35 of Fig. 1.

In an axial bore 10 of a shank or stem 11 is arranged an axially movable needle valve or pin 12 having the usual conical or tapered point 13 for contact with the valve seat 14. 40 In the stem is formed a laterally opening cavity or recess 15, in communication with the bore 10 and forming by its upper and lower walls shoulders 16 and 17, and projecting into said recess or cavity are the 45 arms of a looped thermostatic element 18, the upper arm thereof preferably being secured to the upper shoulder or wall 16, while the lower arm is pivotally and slidably connected with the upper end of the 50 valve or pin 12. Any suitable means of connection may be employed, that which is illustrated in the drawings consisting of a headed stud 19 on the upper end of the valve or pin, and a slot 20 formed in the 55 lower arm of the thermostatic element, said slot engaging the shank of the headed stud.

The recess 15 opens laterally or to one side, and the bore 10 extends from one end of the stem 11 to said recess, there being a yoke portion connecting those portions of the 60 stem at opposite sides of said recess.

The device can be so arranged with respect to any suitable carbureter, that the thermostatic element lies in the path of heated air flowing into the carbureter from a suitable 65 heater, and so that the needle valve controls a valve port having the seat 14. The parts of the improved valve should be adjusted so that when the carbureter is cold the valve will be held by the thermostatic 70 element to give a full opening of the valve port whereas when the carbureter is hot or the intake of air is hot, the valve will be in a position to give the minimum amount of feed of the fuel. Under these circumstances 75 the adjustment of the parts should be effected while the carbureter is heated, and after this adjustment has been effected no further attention need be paid to the device. The limits of movement of the operating 80 arm of the thermostatic element are defined by the shoulders or stops 16 and 17 and when the valve is operated to provide for starting the engine, the carbureter then being cold, a full opening of the valve port 85 will be secured and as the carbureter heats, the thermostatic element will gradually advance the valve until it reaches the limit of closing movement to which the device has been adjusted,—remaining in such position 90 until the cooling or partial cooling of the carbureter induces a reverse movement of the thermostatic element.

It will be understood that owing to the simplicity of the device, it may be applied 95 economically to many of the ordinary types of carbureters, and the thermostatic element and other moving parts being entirely housed by the carbureter, there is no possibility of accidental displacement or disarrangement, and the parts once correctly adjusted will operate as described without further attention on the part of the operator.

Having thus described the invention, what 105 is claimed as new is:

A thermostatic valve embodying a stem having a laterally opening recess extending from one side past its axis and providing opposite shoulders at an angle to said axis, 110 said stem having a bore extending longitudinally from one shoulder to one end

thereof, a needle valve slidable through said bore and projecting beyond said end of the stem and into said recess, that end of the needle valve within the recess having a headed stud, and a looped thermostatic element having one terminal secured to the other shoulder and having its other terminal slotted and engaging said stud.

In testimony that I claim the foregoing as my own, I have hereto affixed my signature in the presence of two witnesses.

EDGAR B. HANDS.
